UNITED STATES PATENT OFFICE.

JACOB OAKES, OF STARBUCK, WASHINGTON.

SPEAR-KNIFE.

1,183,399.

Specification of Letters Patent. Patented May 16, 1916.

Application filed February 18, 1915. Serial No. 9,173.

To all whom it may concern:

Be it known that I, JACOB OAKES, a citizen of the United States, residing at Starbuck, in the county of Columbia and State 5 of Washington, have invented certain new and useful Improvements in Spear-Knives, of which the following is a specification.

This invention relates to improvements in spear knives and its object is to produce a 10 device of this class adapted to securely impale the game as soon as it is struck. Simplicity in construction and efficiency in operation are other objects.

With the foregoing and other objects in 15 view the invention consists in the combination and arrangement of parts to be herein-after fully described in the following specification, pointed out in the claims and illustrated in the accompanying drawings which 20 form a part of said specification and in which—

Figure 1 is a plan view of the knife. Fig. 2 is a longitudinal sectional view taken on line 2—2 of Fig. 6. Fig. 3 is a plan view of 25 the device showing the method by which it securely impales the prey. Fig. 4 is a section taken on line 4—4 of Fig. 2. Fig. 5 is a section taken on line 5—5 of Fig. 2. Fig. 6 is an edge view of Fig. 1.

30 Like reference characters indicate corresponding parts throughout the several views.

The reference numeral 1 designates the handle to which a casting 2 is secured that 35 is formed with oppositely disposed ears 3, 3. The handle is projected to form a casing 4 provided with a partition 5 through which a shank 6 extends that also passes through the casing 4 and is provided with a shoulder 7 40 disposed within the casing and upon which one end of a spring 8 rests which spring also abuts the partition 5. The shank 6 beyond the casing 4 is bifurcated and carries a pin 9 upon which a disk 10 is mounted which 45 frictionally engages the periphery of an approximately semi-circular jaw 11 which is recessed at 11^a to receive said disk and is arranged upon a pivot 12 carried in the longitudinally slotted portion 13 of the blade 14; 50 said blade being further formed with an eye 15 and with a pointed termination 16.

The normal position of the jaw 11 is clearly shown in Figs. 1 and 2 and the purpose of the disk 10 is to frictionally retain the jaw in such position, pressure upon the disk being afforded through the medium of the 55 spring 8.

The knife is thrown or hurled at the game and when it strikes the same the pointed end of the blade enters the flesh until the 60 flesh strikes the jaw 11 at its lowest point thus swinging said jaw upon its pivot, against the tension of the disk 10, and forcing the point of this jaw also into the flesh impaling the game between said jaw and 65 blade in the manner illustrated in Fig. 3.

To release the game from the knife the jaw is manually forced back into original position and the blade withdrawn.

To use as a harpoon the ears 3, 3 will serve 70 to secure the ends of the cord.

What is claimed is:

1. A spear knife comprising a handle, a blade made integral therewith, a curved jaw pivotally associated with said blade and 75 means carried by said handle for frictional engagement with said jaw whereby the same is yieldingly retained in normal position.

2. A spear knife comprising a handle, a blade made integral therewith, a curved 80 recessed jaw pivotally associated with said blade and a spring-pressed friction roller carried by said handle normally in engagement with the recessed portion of said jaw to yieldingly retain the same in normal 85 position.

3. A spear knife comprising a handle, a blade integral therewith, a curved jaw pivotally associated with said blade and means operatively associated with said blade and 90 jaw whereby they are yieldingly retained in fixed relation with each other.

4. A spear knife comprising a handle, a longitudinally slotted blade made integral therewith, a curved jaw pivotally disposed 95 in the slotted portion of said blade and means operatively associated with said blade and jaw whereby they are yieldingly retained in fixed relation with each other.

5. A spear knife comprising a handle, a 100 longitudinally slotted blade formed with an eye and formed integral with said han-

dle, a curved jaw pivotally disposed in the slotted portion of said blade and capable of coöperation with the eye in said blade and means operatively associated with said 5 blade and jaw whereby they are yieldingly retained in fixed relation with each other.

In testimony that I claim the foregoing

as my own I have hereto affixed my signature in the presence of two subscribing witnesses.

JACOB OAKES.
